(57) **CLAIM**

The ornamental design for a display screen or portion thereof with animated graphical user interface as shown and described.

DESCRIPTION

FIG. 1 is a front view showing a first embodiment of a display screen or portion thereof with animated graphical user interface illustrating a first image in a sequence;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is a front view showing a second embodiment of a display screen or portion thereof with animated graphical user interface illustrating a first image in a sequence;

FIG. 9 is a second image thereof;

FIG. 10 is a third image thereof;

FIG. 11 is a fourth image thereof;

FIG. 12 is a fifth image thereof;

FIG. 13 is a sixth image thereof;

FIG. 14 is a seventh image thereof;

FIG. 15 is a front view showing a third embodiment of a display screen or portion thereof with animated graphical user interface illustrating a first image in a sequence;

FIG. 16 is a second image thereof;

FIG. 17 is a third image thereof;

FIG. 18 is a fourth image thereof;

FIG. 19 is a fifth image thereof;

FIG. 20 is a sixth image thereof;

FIG. 21 is a seventh image thereof;

FIG. 22 is a front view showing a fourth embodiment of a display screen or portion thereof with animated graphical user interface illustrating a first image in a sequence;

FIG. 23 is a second image thereof;

FIG. 24 is a third image thereof;

FIG. 25 is a fourth image thereof;

FIG. 26 is a fifth image thereof;

FIG. 27 is a sixth image thereof; and,

(Continued)

FIG. 28 is a seventh image thereof. The appearance of the animated graphical user interface sequentially transitions between the images shown in FIGS. 1-28. The process or period in which one image transitions to another image forms no part of the claimed design. The broken lines showing a device form no part of the claimed design.
